UNITED STATES PATENT OFFICE.

GEOVER P. SHEARER, OF CHICAGO, ILLINOIS.

BASKET.

Application filed January 23, 1926. Serial No. 83,169.

This invention relates to improvements in baskets particularly adapted, though not necessarily limited in its use, for holding plants or flowers.

5 Heretofore in baskets of this character the bottoms have usually been formed of a disc of wood to the periphery of which upright stays have been fastened by means of nails or the like driven through the stays and into 10 the bottom, and the body being formed of reed or willow which is interwoven or interlaced with the stays.

In pedestal baskets the basket proper has usually been placed upon the end of a supporting upright and the two fastened together by driving a nail or the like through the bottom of the basket into the end of the upright.

15 It has been found that the wooden bottoms of such baskets after a short time warp and crack, as well as decay, with the result that the basket soon becomes useless.

Furthermore the reed or willow stays being of a small diameter are frequently split by the 25 fastening nail passing therethrough, the stays being weakened at such points, break and become loosened and detached from the bottom.

It is one of the objects of the present invention to provide an improved basket of this character in which the objectionable wooden bottom and the objectionable nailing of the stays thereto will be dispensed with and in lieu thereof there will be employed a form 35 retaining element, which may be a receptacle, preferably metal, about which the reed or willow is arranged, the stays and parts of the basket being secured to the form through the medium of loops or eyes through which the 40 stays are threaded.

A further object is to provide in a basket of this character a sustaining form for the basket, the body portion of the basket being interlaced therewith, and a filler adapted 45 to be readily inserted thereinto and as readily removed therefrom.

A further object is to provide in an improved basket of this character means whereby the weight of the contents of the basket 50 will not be supported by the basket itself but by the container which rests upon the same support as, and independent of the basket.

A further object is to provide improved 55 means whereby a basket of this character may be readily secured to a supporting base or pedestal.

To the attainment of these ends and the accomplishment of other new and useful objects as will appear, the invention consists in the features of novelty in substantially 60 the construction, combination and arrangement of the several parts, hereinafter more fully described and claimed and shown in the accompanying drawings illustrating this invention and in which:

65 Figure 1 is a perspective view of a filler member for a basket constructed in accordance with the principles of this invention.

Figure 2 is a perspective view of the filler member shown in Figure 1 having a cover of 70 reed or willow woven thereabout.

Figure 3 is a perspective view of another form of basket.

Figure 4 is a detail perspective view of a 75 form sustaining member, constituting a portion of the basket and being independent of the filler member.

Figure 5 is a sectional view taken on line 5—5, Figure 3.

Figure 6 is a detail perspective view of a 80 pedestal form of basket.

Figure 7 is a sectional view taken on line 7—7, Figure 6.

Referring more particularly to the drawings the numeral 10 designates generally a 85 filler member which is preferably in the form of a receptacle constructed of any suitable material such as metal or the like and may be of any desired size and configuration.

Secured to and projecting beyond the periphery of the member 10 at any desired point intermediate the top and bottom thereof, but preferably adjacent the base, are a plurality of loop or eye-like formations 11 which encompass the receptacle. These eyes or loops 90 may project for any desired distance beyond the periphery of the member and may be formed in any suitable manner of any suitable material. If desired they may be formed of wire-like material as shown or may be formed 95 from and by shaping sheet material.

The basket proper constitutes a cover for the receptacle 10 and may be formed of any 100 suitable material such as willow or reed. The basket is preferably formed by means of uprights or stays 12 which are threaded through the eyes or loops 11 and may be arranged in any suitable manner against and about the periphery of the receptacle. The upper extremities 13 of the stays may be arranged to 110 project above the top of the receptacle, and interlaced or interwoven with the stays adja-

cent the top thereof, are fiber members 14 such as reed or willow to form the top part of the basket. The lower extremities of the stays 12 below the eye-like formations 11 5 may be interwoven or interlaced to form a base for the basket adjacent the bottom of the receptacle.

In this form of the invention it will be manifest that the basket and container will 10 be fastened together through the interlacing of the stays with the eyes or loops 11, and by fastening the stays or the basket covering to the receptacle in the manner shown, the necessity of nailing or otherwise fastening 15 the stays or cover to the receptacle will be obviated.

In Figures 3 and 5 of the drawings the eyes or loop-like formations 16 are arranged for a considerable distance above the bottom 20 17 of the receptacle or filler 18, and the stays 19 corresponding with the stays 12 of the form shown in Figure 2 are threaded through the eyes or loops 16. The upper extremities 20 of the stays may terminate slightly above 25 the filler 18 and willow or reed strips 21 are interlaced with these stays, similar to the interlacing 14 of the form shown in Figure 2.

The lower portions 22 of the stays are deflected away from the filler 18 and the extremities 23 of the deflected portions terminate preferably in a line with the base 17 of the filler 18.

Fiber strips 24 such as reed, willow or the like are interlaced with the portions 22 of 35 the stays to form a skirt around the bottom of the base of the filler which flares outwardly and away from the bottom of the filler 18.

With this improved construction it will be manifest that the weight of the filler or receptacle 18 and the contents thereof will not 40 be sustained by the basket, but the filler or receptacle 18 will rest upon the same supporting surface upon which the ends 23 of the stays 22 rest.

45 In Figure 4 there is shown an annular form sustaining member 25 having eyes or loops 26 formed about its periphery.

This form sustaining member is employed to produce a basket independently of the 50 filler or receptacle that is inserted therein.

That is to say, the upright stays are threaded through the eyes or loops 26 in the same manner as in the other forms, and when in use the form 25 may be slipped over one 55 end of a filler or receptacle while the basket is being formed, the basket being formed by interweaving and interlacing strips of fiber material such as reed or willow.

The basket may be formed in any suitable 60 manner either as shown in Figure 2 or Figure 3 in which latter the entire body portion 27 is formed of strips of fiber material interlacing with the strips 20.

When the form sustaining member 25 is 65 employed, and as before stated when placed

over a receptacle or other form, the basket is constructed in the manner shown in either Figures 2 or 3.

After the basket has thus been formed, it will be manifest that the receptacle or filler 70 may then be removed through the basket and the basket will be maintained in this shape by means of the annular member 25.

Obviously any number of these annular members 25 may be employed but it has been 75 found in practice that only one is necessary.

In Figures 6 and 7 there is shown a form of pedestal basket, the basket portion of which may be constructed preferably in a 80 manner shown in Figure 2.

In this form of the invention there is secured to the bottom 17 of the filler 18, a tubular projection 28, which may be fastened in any suitable manner, and preferably centrally thereof. The tubular member 28 is adapted to be telescoped over the upper end of an upright 29 having a base 30.

After the tubular extension 28 is telescoped with the upright or standard 29, the two may be secured together in any suitable manner, such as by means of fastening devices 31 in the form of nails or the like driven through the tubular member and into the standard.

In this form of the invention the stays 32 are threaded through the eyes or loops 33, the lower ends 34 of the stays being deflected inwardly and against the tubular member 28 or the standard 29. The extremities 35 of the portions 34 of the stays 32 may then be fastened in any suitable manner such as by means of a fastening device 36 wound or tied therearound.

If desired the portion of the pedestal 29 beneath the extremities 35 of the stays 32 and the fastening device 36 may be covered in any 105 suitable manner or may be allowed to remain uncovered.

With this invention it will be manifest that the objectionable wooden bottom ordinarily employed in baskets of this character is dispensed with, as is also the necessity of fastening the stays to the bottom by driving nails through the stays into the bottom, with the result that all danger of warping of the bottom, or of the nails becoming loosened from 115 the bottom, or of the stays becoming broken, will be obviated.

Furthermore there will be produced a basket of this character which will be of a rigid and durable construction and at the same 120 time there will be provided a container within the basket for receiving plants or flowers, which will be water proof and which will not become warped or broken under ordinary usage.

125 While the preferred forms of the invention have been herein shown and described, it is to be understood that various changes may be made in the details of construction and in the combination and arrangement of the sev- 130

eral parts, within the scope of the claims, without departing from the spirit of this invention.

What is claimed as new is:—

- 5 1. A basket of the character described embodying a receptacle, laterally projecting eye like formations supported by the periphery of the receptacle and spaced above the bottom thereof, flexible strips threaded through said eyes and extending along the receptacle towards the top thereof, and additional flexible strips interlaced with the first said strips.
- 10 2. A basket of the character described embodying a receptacle, laterally projecting eye like formations supported by the periphery

of the receptacle and spaced above the bottom thereof, flexible strips threaded through said eyes and extending along the receptacle 20 towards the top thereof, and additional flexible strips interlaced with the first said strips, the lower portion of the first said strips being deflected outwardly to form a support, the bottom of the receptacle resting upon a supporting surface whereby the flexible 25 strips will be relieved of the weight of the receptacle.

In testimony whereof I have signed my name to this specification, on this 12th day of January, A. D. 1926.

GROVER P. SHEARER.
